UNITED STATES PATENT OFFICE.

CLARENCE B. WESTON, OF MARION, OHIO, ASSIGNOR TO BALL ENGINE COMPANY, OF ERIE, PENNSYLVANIA, A CORPORATION OF PENNSYLVANIA.

POWER-SHOVEL.

1,254,295.

Specification of Letters Patent. Patented Jan. 22, 1918.

Application filed January 20, 1915. Serial No. 3,359.

To all whom it may concern:

Be it known that I, CLARENCE B. WESTON, a citizen of the United States, residing at Marion, in the county of Marion and State of Ohio, have invented new and useful Improvements in Power-Shovels, of which the following is a specification.

This invention relates to power shovels and consists in certain improvements in the construction thereof as will be hereinafter fully described and pointed out in the claims.

In power shovels as now commonly constructed a dipper stick is operated in relation to a boom. This is accomplished by mounting a shipper shaft on the boom and securing pinions to the shipper shaft which operate in racks on the dipper stick. These pinions from the nature of their relations are limited in width and are subjected to such exceptional strains as to make it very difficult, in fact, almost impossible to so secure them to the shipper shaft as to prevent their loosening under the conditions of use. The object of the present invention is to obviate this difficulty.

The invention is illustrated in the accompanying drawings as follows:—

Figure 1 shows a side elevation of the front end of a power shovel.

Fig. 2 a section on the line 2—2 in Fig. 1.

Fig. 3 a detached view, partly in section, of the shipper shaft.

1 marks the frame of the shovel, 2 the wheels on which it is mounted, 3 the turn table, and 4 the boom, the boom being connected with and supported by the turn table in the usual manner. The boom ordinarily is formed with two side members and the dipper stick 5 commonly operates between these side members. Dipper sticks also are sometimes formed in pairs, and as shown is so formed. The dipper 6 is secured to the dipper stick. The hoisting cable 7 is secured to the dipper and runs over a block 8 at the upper end of the boom in the usual manner, the cable being carried back to the power mechanism (not shown).

Shipper shaft bearings 9 are mounted on the side members of the boom and the shipper shaft 10 is journaled in these bearings extending across the space between the side members and slightly outside of at least one of the side members. The shipper shaft has the gears 11, these gears being arranged as shown on the shaft between the bearings 9.

Racks 12 are secured to the members of the dipper stick and mesh the gears or pinions 11. The gears are provided with the shrouds 13 which form rolled surfaces on which the corresponding shrouds 13^a on the racks ride, thus forming a rolling support for the dipper stick.

A retaining member or yoke 14 is journaled on the shipper shaft between the gears 11 and in the construction shown extends outwardly between the members of the dipper stick and has the lateral projections 15 which form a sliding engagement with the dipper stick and retain the dipper stick in position with relation to the gears so as to maintain the racks and pinions in mesh.

A gear 16 is secured to the outer end of the shaft and this is driven by the crowding engine 17 through any convenient mechanism.

Where the dipper stick is formed with two members and two shipper shaft gears or pinions are used, it will be observed that these gears tend to hold the dipper stick in alinement, that is to say, prevent a swaying movement of the dipper stick in a direction transversely to the boom. Under these conditions, it will be seen one gear is forced in one direction and the other gear in the opposite direction when the dipper is subjected to side strain. This with the other strains to which these gears are subjected make it almost impossible to so secure them to the shaft as to maintain them in a position fixed with relation to the shaft. Various expedients have been attempted for correcting this trouble as by squaring the shaft and by forming the gears and shaft of special metal. The difficulty is aggravated by the limited space which the gears must occupy. By forming the gears integral with the shaft, preferably by casting in the form of a steel casting and then turning the shaft, using the gears for centering the operation a construction is provided in which the gears remain permanently in their relation on the shaft and the difficulties heretofore experienced are entirely obviated.

What I claim as new is:—

1. In a power shovel, the combination of a boom formed with side members; a dipper stick operating between the side members of the boom; shipper shaft bearings on the side members; a shipper shaft journaled in said bearings; a shipper pinion formed integrally with the shipper shaft; and a gear secured to the shipper shaft between the bearings, the gear meshing with the shipper pinion.

with the shaft and located between the bearings; a rack on the dipper stick meshing with the pinion; and a retaining member journaled on the shaft between the bearings 5 and having a sliding engagement with the dipper stick.

2. In a power shovel, the combination of a boom; a dipper stick operating in relation to said boom; a shipper shaft bearing on the 10 boom; a shipper shaft journaled in said bearing; two shipper shaft pinions formed integrally with the shaft; racks on the dipper stick meshing said pinions; and a retaining member journaled on the shaft and having 15 a sliding engagement with the stick.

3. In a power shovel, the combination of a boom formed with side members; a dipper stick operating between the side members of the boom and formed of two members; shipper shaft bearings on the side members of the boom; a shipper shaft journaled in said bearings; two shipper pinions formed integrally with the shaft and located between the bearings; racks on the members 30 of the dipper stick meshing with said pinions; and a retaining member journaled on the shaft between the pinions and having a sliding 35 engagement with the dipper stick.

of the dipper stick meshing with said 25 pinions; and a retaining member journaled on the shaft and having a sliding engagement with the dipper stick.

4. In a power shovel, the combination of a boom formed with side members; a dipper 30 stick operating between the side members of the boom and formed of two members; shipper shaft bearings on the side members of the boom; a shipper shaft journaled in said bearings; two shipper pinions formed integrally with the shaft and located between the bearings; racks on the members of the dipper stick meshing with said pinions; and a retaining member journaled on the shaft 35 between the pinions and having a sliding 40 engagement with the dipper stick.

In testimony whereof I have hereunto set my hand in the presence of two subscribing witnesses.

CLARENCE B. WESTON.
